United States Patent Office

Des. 229,637

Patented Dec. 18, 1973

229,637

SPIROMETER

John Y. Pun, Richmond, Calif., assignor to Comprehensive Health Testing Laboratories, Inc., San Francisco, Calif.

Filed Oct. 7, 1971, Ser. No. 187,597

Term of patent 14 years

Int. Cl. D24—01

U.S. Cl. D83—1 F

Fig. 1

Fig. 2

Fig. 3

Fig. 4

FIG. 1 is an isometric view of the spirometer showing my new design.

FIG. 2 is a top plan view thereof.

FIG. 3 is a front elevational view thereof.

FIG. 4 is a side elevational view thereof.

The undisclosed rear surface of the spirometer shown is substantially flat and unornamented.

I claim:

The ornamental design for a spirometer, as shown and described.
